GROUNDING MECHANISM FOR MAGNETOS

Herman L. Hartzell, Anderson, Ind., assignor to
General Motors Corporation, Detroit, Mich., a
corporation of Delaware

Application June 6, 1944, Serial No. 538,936

8 Claims. (Cl. 171—209)

The present invention relates to connector units for the primary circuit of magnetos and more particularly to units for magnetos with permanently connected generator windings so as to suppress interference with operation of adjacent radio apparatus and also to provide a ground connection so as to prevent the magneto from generating ignition voltage when a part normally attached to magneto is removed and which maintains the ground connection until said removable part is restored to remove the ground connection.

An object of the present invention is to provide a novel constructed grounding device wherein an electrical condenser and a terminal structure assembly are mounted in a metal housing to provide a unitary structure and wherein the conducting core of the condenser cooperates with the housing to form a ground connection when the terminal assembly is removed from the structure.

Another object of the present invention is to provide a unitary structure, a combined condenser unit and terminal structure for electrical conductors, by which an improved construction and arrangement of parts is had, the structure having a plurality of screw threaded connections, wherein in one device there is a plurality of ground connections provided, together with means for suppressing interference with operation of adjacent radio apparatus.

Another object of the present invention is to provide a grounding device which is simple, compact, durable, and which may be readily attached or removed and still be effective in operation in all positions when mounted on the magneto.

Further objects and advantages of the present invention will be apparent from the following description reference being had to the accompanying drawing wherein a preferred embodiment of the present invention is clearly shown.

In the drawing:

Fig. 1 is an end view of the unitary grounding device embodying the present invention.

Fig. 2 is a sectional view taken on the line 2—2 of Fig. 1 and showing the device in its normal position.

Fig. 3 shows partly in section and partly diagrammatically, a plan view of a circuit interrupter mechanism having a housing which supports the grounding device.

Referring to the drawing, particularly Figs. 1 and 2, the grounding device 10 comprises a metal bushing or housing 20 having a through bore 21, constricted to provide shoulders of three different diameters, the largest portion of the bore being at the left end of the bushing, as viewed in

Fig. 2, while the smallest portion of the bore is located intermediate the ends of the bore to provide an internal ledge 23 to provide a ground portion:

The larger portion of the bore receives a condenser assembly 24 which includes a condenser body comprising two foil strips insulated from each other by a paper strip or strips wound upon a non-conducting tube 25; a well known construction and arrangement. The right margin of one of the foils engages a metal disc 26 while the left margin of the other foil engages a metal cup-member 27. An insulating disc 28 and the condenser body is then assembled upon a conducting core 29 with the disc 28 bearing against a shoulder 31 provided by an enlarged portion 31 of the core. The enlarged portion 31 of the core carries a contact spring 32. An apertured soft rubber washer 33, an apertured insulating disc 34 and a metal washer 35 are then assembled upon one end of the core after which said end is riveted over as at 36 against the washer 35 to clamp the elements 35, 34, 33, 27, 25, 29 between enlarged portion 31 and the riveted-over portion 36 of the core to complete the condenser assembly.

Before the condenser assembly is placed into one end of the bore 21 an insulating lining or sleeve 40, a conducting disc 41 and a conducting resilient member or helical spring 43 are placed in a reduced portion of the bore 21 and arranged so that one end of sleeve 40 and the disc 41 will contact the ledge or shoulder 23. It will be noted that the disc 41 and the spring 43 are smaller in cross dimension than the internal diameter of the sleeve 40 thus the disc 41 and the spring 43 can move axially relative to the sleeve 40, but the sleeve 40 prevents the washer and spring from moving laterally to contact the marginal side walls of the bushing 20. With the sleeve 40, disc 41 and spring 43 in position the condenser assembly 24 is then positioned in this instance in the largest diameter of the bore with the washer 34 adjacent a shoulder. The condenser assembly 24 is then secured within the housing by spinning over a part of the housing as at 44 against the insulation washer 28. By this arrangement the spring provides the conducting connection between the core 29 and the disc 41.

The other end of the bore receives a terminal assembly 50 comprising an insulating tube 51 having a portion of a hollow metal insert 52 embedded therein. The portion of the insert which is exposed is provided with threads on which is screwed a contact 53 which engages the

metal disc 41. Before the contact 53 is attached to the insert a shielded cable 54 extends into the sleeve and insert and has bared end comprising strands spread outwardly over the end of the insert so that the strands are clamped between the end of the insert and the bottom of the tapped recess provided by the contact 53. A rubber grommet 55 and an insulating washer 56 are threaded on the cable, said grommet engages the right hand end of the sleeve 51 while the washer 56 bears against the rubber grommet. The terminal assembly is secured within the bore of the housing by a nut 57 having internal threads engaging external threads provided by the housing. When the nut 57 is threaded upon the sleeve the washer 56 and the grommet 55 causes the sleeve 51 to move inwardly urging the contact 53 into good electrical contact with the disc 41 and to force the disc away from the ground shoulder 23 and thus out of electrical contact with the housing 20 as shown in Fig. 2. The nut 57 is releasably locked in position by a spring finger 57a cooperating with serrations 57b on the nut. Thus, when the grounding unit is assembled as shown in Fig. 3 electrical connection is maintained between a 10 grounding switch 58 and a leaf spring 59 of a magneto 60.

Referring to Fig. 3 the magneto 60 has permanently connected primary and secondary generating windings 61 and 62, respectively, and a housing 63 for the circuit interrupter mechanism arranged in a circuit of the primary winding 61. The circuit interrupter mechanism shown comprises a lever 65 having a rubbing block which is urged by a spring 66 into engagement with a lobe of a cam 67 attached to a shaft 68 of a rotor of the magneto. The lever 65 is periodically operated by the lobes on the cam. Upon each operation of the lever the rubbing block engages a spring pressed arm 69 to separate carrying contact 70 from contact 71 attached to an ear 72 of a plate 73 adjustably mounted upon a plate 74. The plate 74 is grounded to the housing 63 and the lever 69 is supported from a terminal 75 insulated from the plate 74, said terminal is normally the live terminal of the circuit interrupter. The core 29 of the condenser assembly is connected with the terminal 75 by the leaf conductor 59 and the spring 32 to shunt the contacts 70 and 71. The live terminal 75 is connected by wire 77 to one end of the primary winding 61 and one end of the secondary winding 62. The other end of the primary is grounded by the housing 63 and the other end of the secondary is connected to a distributor rotor 79 to distribute ignition voltage, generated by the magneto upon separation of contacts 70, 71 to the spark plugs 80 in the well known manner.

It is pointed out that when the grounding device 10 is removed from housing 63 the strap 59 which is biased will engage the housing 63 as indicated by the broken lines 59a. In the dot-and-dash position of the strap the magneto is grounded and renders same incapable of generating ignition voltage upon periodic separation of the contacts 70, 71. When the bushing 20 is attached to the housing without the terminal assembly therein the magneto will be grounded even though the spring strap is not in contact with the housing because the strap will be electrically connected with the housing 63 through spring 32, condenser core 29, spring 43 and disc 41 which is forced against the metallic shoulder 23. When the terminal assembly is positioned within the bushing 20 the contact 53 will engage the disc 41 to urge

same from the shoulder 23, thus the magneto is rendered operative provided the cable is not grounded.

5 The cable 54 is electrically connected to the manually operated grounding switch 58, which may be operated at will to ground the magneto to deprive the engine of ignition.

10 Thus, as will be apparent to those skilled in the art, the magneto may be rendered incapable of generating ignition voltage in various ways; first, by removing the grounding device to allow the strap to engage the housing by its own resiliency; second by the removal of the terminal assembly from the bushing to allow the disc 41 to contact shoulder 23. It is pointed out here that it is possible to ground the magneto without removing the terminal assembly. This is accomplished by moving the nut 57 to the right-hand end of the bushing 20 sufficiently to allow the disc 41 to engage the shoulder 23 and third, by closing the switch 58.

15 20 25 While the embodiment of the present invention as herein disclosed, constitutes a preferred form, it is to be understood that other forms might be adopted, all coming within the scope of the claims which follow.

What is claimed is as follows:

30 35 40 45 1. A condenser and magneto primary grounding unit adapted to be detachably attached to a magneto housing comprising, a metal body provided with a through opening and being internally restricted intermediate its ends to provide an abutment; a condenser unit having a metal core fixed in one end of the opening so that the inner end of the core is spaced from the abutment; a coil spring of conducting material disposed between the core and the abutment, said core, spring and abutment when in their normal position cooperate to provide a ground connection when the body is attached to the housing; conducting means insulatingly supported at the other end of the body and adapted to engage electrically the spring; and means for moving the conducting means against the biasing force of the spring to compress the spring out of engagement with the abutment to break the ground connection.

50 55 60 65 2. A condenser and a magneto primary grounding unit adapted to be detachably attached to a magneto housing comprising; a metal body provided with a through opening therein and having an internal abutment intermediate its ends; insulation lining a portion of the opening on one side of the abutment; a metal disc movable within the lining and capable of engaging the abutment; a condenser unit having a metal core supported in one end of the opening with the core spaced from the abutment; a coil spring electrically connected with the core for urging the disc against the abutment, said core, spring, disc when in their normal positions cooperating with the housing to provide a ground connection; and movable means insulatingly supported at the other end of the opening and operable to move the disc from the abutment to break the ground connection.

70 75 3. A condenser and a magneto primary grounding unit adapted to be detachably mounted on a metallic housing comprising in combination; a metal bushing having a bore extending therethrough and being restricted intermediate its ends to provide a shoulder; a condenser body having a metallic core fixed within one end of the body so that the inner end of the core is spaced from the shoulder; a disc member reciprocatively

movable within the bore and between the shoulder and inner end of the core; a helical biasing spring of electrically conducting material between the core and the disc to bias the latter against the shoulder to provide a ground connection for the core; terminal means insulated from the housing normally engaging the disc; and means detachably mounted on the bushing for actuating the terminal which when fastened to the bushing moves the terminal against the bias of the spring to move the disc away from the shoulder to break the ground connection, and which when removed from the bushing permits the spring to move the disc against the shoulder to make the ground connection.

4. A grounding unit for the primary circuit of a magneto comprising the combination, of a metal bushing adapted to be detachably mounted to a metal housing of a high tension ignition device and having a central bore therethrough and being internally restricted intermediate its ends to provide a shoulder; an insulating tube having a sliding fit within the bushing and bearing against the shoulder; a metal disc loosely supported within the tube; a condenser unit fixed within the metal bushing and adapted to seat against a second shoulder to hold the insulating tube against the first shoulder, said condenser unit having a metal core having one end extending beyond one end of the metal bushing and having the other end extending into the insulating tube; a helical spring of electrical conducting material having one end in conducting relation with the condenser core and having the other end engaging and biasing said metal disc against said first shoulder to provide a ground connection; an internally threaded sleeve threadedly engaged with an externally threaded portion of the body; and conducting means insulated from the sleeve and engaging said disc said sleeve when threaded a certain distance causes the conducting means to move the disc from the first shoulder against the biasing force of the spring to break the ground connection between the metal disc and the metal housing.

5. A unit for support and anchorage of a condenser unit and an insulated conductor in a high tension ignition system comprising in combination; a metal body adapted to be detachably mounted with a metal housing and having a through bore provided with an internal shoulder; an electrical condenser having a metal core positioned within one end of the bore so that one end extends outside the body and the other end is suitably spaced from one side of the shoulder; a spring and a metal disc disposed between the core and shoulder, said spring operating to urge the disc against the shoulder to provide a ground connection through the body; a terminal assembly including an insulating bushing slidably mounted within the bore and positioned on the other side of the shoulder; an insulated wire having one end extending through the bushing, and a conductive member detachably mounted on said end of the cable in conducting relation with the wire thereof, holding the assembled

bushing cable and member in fixed position said member extending loosely past the shoulder and into engagement with the disc; and means having threaded engagement with the body for actuating the terminal assembly against the bias of the spring to move the disc away from the shoulder to break the ground connection between the disc and the body.

6. A condenser and magneto primary grounding unit adapted to be detachably attached to a magneto metal housing comprising, a metal body having threaded engagement with the housing, said body having a through opening and being provided with an internal ledge; a condenser having a metal core supported on one side of the ledge with one end of the core spaced from the ledge; a yieldable conducting means having one end engageable with the core and the other end engageable with the ledge to provide normally a ground connection through the body; an insulating sleeve slidably supported by the body and located on the other side of the ledge; a contact member carried by the sleeve and cooperating with said spring to control the ground connection through the body; and means detachably carried by the body and operable to actuate the sleeve for urging same in a direction causing the contact to move the spring out of engagement with the ledge.

7. In combination with a magneto housing having an opening in one wall thereof; a readily attachable and detachable primary grounding unit adapted to fit in the opening, said unit including a hollow metal body, a condenser unit having a metal core fixed in one end of the body, a conducting spring adapted to connect the core with the body to provide a ground connection through body, an insulated conductor disposed movably at the other end of the body and adapted to engage the spring, and detachable means for holding the conductor in assembled relation with the body, said means being adjustable to enable the conductor to be moved to compress the spring so that the latter is moved out of engagement with the body to break the ground connection through the body.

8. A condenser and a magneto primary grounding unit adapted to be detachably attached to a magneto metal housing comprising, a hollow metal body; a condenser unit having a metal core supported in one end of the body; a conducting spring having one end electrically connected with one end of the core and having the other end adapted to engage a part of the body to provide a ground connection through the body; insulation lining a portion of the body and surrounding the spring between the condenser and the part; and detachable means insulatingly supported at the other end of the body and operable to compress the spring end out of engagement with the part and within the confines of the lining to break the ground connection and maintain the spring in its compressed state until the detachable means is substantially removed from the body.
